DESIGN FOR A GLASS BOTTLE

Lawrence J. Kihn, Pittsburgh, Pa., assignor to
J. T. & A. Hamilton Company, a corporation
of Pennsylvania

Application November 6, 1935, Serial No. 59,401

Term of patent 14 years

To whom it may concern:

Be it known that I, Lawrence J. Kihn, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part thereof.

In the drawing: Fig. I is a rear elevation of a glass bottle showing my new design, the ornamentation of the bottle being fragmentarily shown, but it being understood that such ornamentation extends over the surface of the bottle

exterior to the unornamented areas shown thereon within enclosing lines.

Fig. II is a front elevation of the said glass bottle, shown similarly to the presentation of the glass bottle in Fig. I;

Fig. III is a fragmentary portion of the bottle showing an enlarged detail of the surface ornamentation, which ornamentation consists of lozenge-shaped areas, each of such lozenge-shaped areas closely enclosing a single, conical prism.

I claim:

The ornamental design for a glass bottle, substantially as shown and described.

LAWRENCE J. KIHN.
